LAUNDRY MACHINE CABINET OR SIMILAR ARTICLE

Carl W. Sundberg, Birmingham, Mich., assignor, by mesne assignments, to Whirlpool-Seeger Corporation, St.
Joseph, Mich., a corporation of Delaware

Application August 5, 1954, Serial No. 31,741

Term of patent 14 years

(Cl. D49—1)

FIG. 2

Figure 1 is a front perspective view of a laundry machine cabinet or similar article showing my new design; and

The essential features of the design reside in the portions shown in full lines.

I claim:

The ornamental design for a laundry machine cabinet or similar article, as shown and described.
